UNITED STATES PATENT OFFICE.

ENEZ MEDA, OF NEW YORK, N. Y., ASSIGNOR TO BLANCK & CO., INC., OF NEW YORK, N. Y.

DESIGN FOR EMBROIDERED LACE.

Application filed June 18, 1925. Serial No. 13,815. Term of patent 3½ years.

To all whom it may concern:

Be it known that I, ENEZ MEDA, a citizen of Italy, residing at New York city, in the county and State of New York, have invented a new, original, and ornamental Design for Embroidered Lace, of which the following is a specification, reference being had to the accompanying drawing, forming a part thereof.

The figure is a plan view of embroidered lace showing my new design.

I claim:

The ornamental design for embroidered lace, as shown.

In testimony whereof I affix my signature.

ENEZ MEDA.
